UNITED STATES PATENT OFFICE.

JOHN G. DEBBELER AND FRANK J. KIRSCH, OF COVINGTON, KENTUCKY.

GREASE-CUP.

1,211,419.

Specification of Letters Patent.

Patented Jan. 9, 1917.

Application filed August 5, 1916. Serial No. 113,239.

To all whom it may concern:

Be it known that we, JOHN G. DEBBELER and FRANK J. KIRSCH, citizens of the United States, and residents of the city of Covington, in the county of Kenton and State of Kentucky, have invented certain new and useful Improvements in Grease Cups and the like, of which the following is a full, clear, and exact description, reference being 10 had to the accompanying drawing, forming part of this specification.

In the providing of grease cups for moving parts of machinery, particularly of locomotives and such like, there has been considerable difficulty in the past in providing a fully practical self-advancing grease feed, which will not be liable to loss of parts while the machine is in operation, and which will not clog up and become ineffective under any 20 conditions.

Our grease cup, as shown, is particularly adapted for use with locomotive side rods, but it will be understood that it can be readily modified or used without modification on other pieces of machinery.

It is our object to provide a self-advancing feed of grease for hard grease which has a visible member to indicate the amount of grease in the device, and at the same time to 30 fully protect the springs which operate the self-advancing means against becoming clogged.

We have found that in spring feeds for grease cups, there is likely to result a collection of hard grease around the spring which prevents it from working. We have found that the plungers in the grease retaining parts are likely to become hard and thus will not hug the walls of the retainers.

Again we have found that the parts of the cup have a tendency to jar loose and become lost, or in a locomotive side rod, for example, to fly off and injure any person standing near by.

Thus it is our object to remedy the above defects, and these various objects we accomplish by that certain construction and arrangement of parts which will be herein-

after more specifically pointed out and claimed.

In the drawing, Figure 1 is a central longitudinal section of the device complete, showing the self-advancing feed in fully advanced position. Fig. 2 is a side elevation of the same. Fig. 3 is a bottom plan view of 55 the expandible washer or piston which feeds the grease.

The member for receiving the grease is indicated at 1, and into it screws a barrel 2, which is the grease container. On the end 60 of this barrel is screwed the adjustable cap 3, which has a suitable aperture in its head for the plunger 4. As the cap holds in the barrel the parts of the self-advancing feeding device, it is provided with a lock as follows: The cap is notched at 5 in one or more places along its lower edge, and soldered or otherwise secured to the side of the barrel is a spring finger 6 which is adapted 65 to seat in the notch. As is customary, the 70 notch has one sloping face whereby the finger will slip by when the cap is being screwed down on the barrel, but will catch when the cap is moved in the opposite direction.

Mounted between two clips 7, 7, at each side of the base of the spring finger, is a pin 8 having a bend at 9, and formed at its outer end into a handle 10. When the handle is lying flat along the barrel, the bend at 9 80 will also lie flat therewith. But when the handle is thrown upwardly, then the bend 9 will be swung out and will raise the finger away from the notch in the cap.

Extending into the barrel through the cap 85 is the plunger above referred to which has a series of holes 11 therein to permit of inserting a cotter pin 12, which will serve to lock, or hold in place the plunger, while the plunger with the spring is being drawn taut 90 or compressed tightly so as to permit the cap to be easily screwed onto the barrel, after it has been filled with grease.

Mounted on the end of the plunger is the special washer or piston 13. This washer 95 has a depending flange 14 and inside of the

flange is set a split ring 15 which serves to keep the flange spread out so as to closely fit the walls of the barrel. A metal plate 16 is set on the ring at the bottom and is secured to the plunger by means of a screw or in any other desired manner.

Mounted loosely over the plunger within the barrel are a set of preferably three telescoping cylinders 17 of light metal, one fitting within the other so as to be held by frictional contact in the various positions of telescopic adjustment. In the construction in which frictional contact is relied upon to hold the cylinders together, it is of course essential that the external diameter of each cylinder shall be slightly greater at its inner end than the internal diameter at the outer end of the cylinder within which it telescopes, so as to prevent separation of the telescopic members. This difference of diameter is too slight to be illustrated in the drawings, but will of course be understood. In other words, the cylinders are slightly conical, as is usual in such telescopic members, but only sufficient to hold them in frictional engagement. The upper and lower cylinders are provided with inwardly extending ends 18 and set loosely around the plunger within the cylinders is a spring 19 which engages these two ends. The cylinders are free to slide with regard to each other and are for the purpose of preventing hard grease from accumulating about the spring and stopping its activity.

When in use the barrel is filled with grease, and the cap screwed onto it carrying the various parts now described. The screwing down of the cap will cause the spring to force the cylinders apart, as the cap will bear on the upper cylinder, and the spring will be compressed because the grease will prevent the lower cylinder and the plunger and washer from descending very far into the barrel. As the grease is used up, the spring will separate the cylinders more and more, and thus the lower cylinder will force down the washer and the plunger. The plunger will indicate how full the barrel is of grease, and the screwing down of the cap will permit of a further depression of the washer by tightening up the spring. As the washer will be tight at all times, and as the cylinders are of a length to prevent the entire separation of them when the barrel is fully empty (Fig. 1), there will be no grease left which can get inside of the cylinders to clog up the spring.

Thus it will be seen that the self-advancing feed, the protection against loss of parts, the prevention of clogging of the spring, and the various other objects of our invention are fully accomplished by the above structure.

It is not desired because of the failure to mention the various equivalent structures in

the above mechanism to imply a limitation in the claims that follow to any narrower interpretation than a fair construction of their language will provide.

Having thus described our invention, what we claim as new and desire to secure by Letters Patent, is:—

1. In a grease cup, the combination with a grease retaining member, a set of telescoping members therein, a top member for said retaining member adapted to bear on said cylinders, a piston within said retaining member adapted to be maintained in contact with the said cylinders, and spring means within the cylinders for causing the extension thereof with the consequent depression of the piston in the retaining member. 75

2. In a grease cup, the combination with a grease retaining member, a set of telescoping members therein, a top member for said retaining member adapted to bear on said cylinders, a piston within said retaining member adapted to be maintained in contact with the said cylinders, and spring means within the cylinders for causing the extension thereof with the consequent depression of the piston in the retaining member. 85

3. In a grease cup, the combination with a grease retaining member, a set of telescoping members therein, a top member for said retaining member adapted to bear on said cylinders, a piston within said retaining member adapted to be maintained in contact with the said cylinders, and spring means within the cylinders for causing the extension thereof with the consequent depression of the piston in the retaining member, said top member comprising a cap threadably mounted on the retaining member, and a spring finger on said retaining member and adapted to engage said cap to prevent rotation thereof. 95

4. In a grease cup, the combination with a grease retaining member, a set of telescoping members therein, a top member for said retaining member adapted to bear on said cylinders, a piston within said retaining member adapted to be maintained in contact with the said cylinders, and spring means within the cylinders for causing the extension thereof with the consequent depression of the piston in the retaining member, said top member comprising a cap threadably mounted on the retaining member, and a spring finger on said retaining member adapted to engage said cap to prevent rotation thereof, said finger being provided with means for throwing it out of engagement with said cap. 115

5. In a grease cup, a cylindrical barrel, a plunger adapted to move in said barrel, a washer on the end of the plunger, said washer having expandible means in contact 130

therewith to keep it in constant contact with the walls of said barrel, a set of telescoping cylinders loosely mounted over the plunger, a spring within the cylinders and will be spring-advanced in the barrel, and the grease therein will be prevented from contact with the spring with the consequent 10
5 bearing on the upper and lower ones of said set, and a cap for said barrel adapted to contact with the cylinders whereby the washer clogging thereof.

JOHN G. DEBBELER.
FRANK J. KIRSCH.
